UNITED STATES PATENT OFFICE.

FREDERICK J. LEE, OF OSWEGO, KANSAS.

DOOR-LATCH.

SPECIFICATION forming part of Letters Patent No. 286,985, dated October 16, 1883.

Application filed May 18, 1883. (Model.)

To all whom it may concern:

Be it known that I, FREDERICK J. LEE, of Oswego, in the county of Labette and State of Kansas, have invented certain new and useful 5 Improvements in Door-Latches; and I do hereby declare that the following is a full, clear, and exact description thereof, reference being had to the accompanying drawings, and to the letters of reference marked thereon, which form 10 part of this specification, in which—

Figures 1 and 2 are perspective views of my improvements in latches applied to a door, taken from reverse sides thereof. Fig. 3 is a horizontal section through a part of a door and 15 its frame, with my improved latch and lock applied. Fig. 4 is an inside view of part of a door, showing my improved locking-lever in two positions by the aid of full lines and dotted lines. Fig. 5 is a detail view of a modification.

This invention relates to novel improvements in a face-plate having a looped guard, in combination with a slotted lever, which is adjustable over or beneath the shank of the latch, for the purpose of locking it either up or 25 down, all of which will be fully understood from the following description, when taken in connection with the annexed drawings. The combined latch and lock which I am about to 30 describe is an improvement on the devices which are described and claimed in my Letters Patent numbered, respectively, 250,551, of 1881, and 260,693, of 1882.

A designates part of a door-frame having a 35 vertical beveled strip secured to it, to which is fastened a wearing catch-plate, a; and B designates part of a door to which my improved device is applied. On the inner side of the door, at a suitable point, I rigidly secure a 40 face-plate, C, having a slot, b, through it, which registers with a corresponding slot through the door, and also through a bearing-plate, D, secured to the outside of the door. The plate C is formed with a looped guard, c, for the lock- 45 ing-tongue d of a flat locking-lever, E, which has a T-shaped slot, e, through it, and a finger-piece or handle, f, on one end. This slotted locking-lever is attached loosely to the face-plate C by means of a stud, g, having a head 50 on it, which stud is the fulcrum for the lever.

G designates a lever-latch, which is constructed with a hooked inner end, (shown at h,) for the purpose of engaging with the wearing-plate a. It is also constructed with a thumb-piece, i, a fulcrum-notch, j, a segment, k, and a notched lug, l. The notch j engages with the edge of the slot through the bearing-plate D, which edge affords the fulcrum for the latch G. The segment k, which is formed on the shank of the latch opposite the notch j, is 60 designed to prevent displacement of the latch from plate D, and the notched lug l is designed for holding one end of a helical spring, S, the opposite end of which is held by a similar notched lug, l', which is formed on the back 65 of the bearing-plate D, as shown in the sectional view, Fig. 3.

It will be observed that when the spring S is in its place it assumes the form of the arc of a circle which is concentric to the fulcrum 70 or axis of motion of the latch. The spring thus applied is not only active, but it is securely held in place, and by this mode of applying it a spring-box or a large mortise in the door is rendered unnecessary.

When it is desired to lock the door, the tongue d of the locking-lever E is adjusted over the shank of the latch. When it is desired to render the latch inactive, the tongue d is adjusted beneath the shank of the latch, 75 and when it is desired to release the latch the locking-lever E is drawn back, so that the tongue d does not engage with the shank of the latch. These three adjustments are allowed by providing the locking-lever with the 80 T-shaped slot e.

It will be observed that I have arranged below the locking-lever a thumb-piece, T, or fulcrum, which may be a knob or a hook adapted to afford a purchase for the thumb when it is 85 desired to lift the latch by said locking-lever.

It is obvious that the locking-lever may have more than one notch springing from its longitudinal slot, and that the handle or lip l may form an integral part of this lever, or be a 90 separate piece secured to it in any suitable manner. I may use a spring in combination with the drop-latch, if desired. I do not confine myself thereto.

Having thus fully described my invention, 95

what I claim as new, and desire to secure by Letters Patent, is—

The combination, with a lever-latch, of a slotted face-plate, a loop or guard, *c*, and a locking-lever constructed with longitudinal and transverse slots, substantially in the manner and for the purposes described.

In testimony that I claim the foregoing as my own I affix my signature in presence of two witnesses.

FREDERICK J. LEE.
